VARIABLE TRANSFORMER

William H. Laurie, Plainville, Conn., assignor to The Superior Electric Co., Bristol, Conn., a corporation of Connecticut

Application November 23, 1956, Serial No. 623,908

6 Claims. (Cl. 336—141)

The present invention relates to a variable transformer and, more particularly, to such a device having a winding provided with a conducting surface.

An object of the present invention is to provide in a variable transformer having a stationary winding with a collecting surface and a brush, a brush actuating mechanism which causes the brush to engage only one turn of the winding at a time throughout the limits of travel of the brush.

Another object of the present invention is to provide a brush actuating mechanism which causes the brush to move in a helical path.

A further object of the instant invention is to provide in a variable transformer having a helical winding, a brush actuating mechanism which moves the brush in a helix having the same helical dimensions as the winding.

An object of the present invention is to provide a brush moving mechanism which is extremely simple in operation, reliable in use over an extended period, economical to manufacture and very compact.

A further object of the present invention is the provision of a variable transformer having a winding that remains stationary and a brush rotatable thereabout in which a brush actuating mechanism is so constructed and arranged as to prevent circulating currents from being induced into the mechanism.

In application, Serial No. 467,781, filed November 9, 1954, entitled Voltage Regulating Apparatus, by Gustav O. Fredrickson, now abandoned, there is disclosed a variable transformer which is an autotransformer in which a helical winding is caused to rotate and a brush is moved parallel to the axis of the winding to effectuate the desired transformation of the input voltage. However, though satisfactory, such a device necessitated a complex bearing structure to support the winding for rotation and such structure as heretofore constructed did not provide for a sufficiently reliable usage over an extended period. Also a re-entrant ring was required for each tap in the winding in addition to a ring for each connection to the ends of the winding and thereby the device was limited as to the plurality of voltages for which it could serve.

It is a further object of the above invention to provide a variable autotransformer in which only a simple bearing structure is required that is reliable in use over an extended period and in which only a single re-entrant ring is required, irrespective of the number of connections to the winding.

A feature of the present invention resides in the brush actuating mechanism having a pair of spaced-apart rings with a plurality of rods extending therebetween. The rings are positioned adjacent each end of a helically wound winding with the rods located about the periphery of the winding. A brush holder is carried for sliding movement axially along the rods and has brushes engageable with the winding. One of the rings is rotated either manually or by a motor and the brush is carried along a circular path about the periphery of the stationary coil.

Also carried by the rings is at least one screw rod extending therebetween and the brush has a threaded aperture mating with the screw rod. The threads of the rod have the same pitch or length of axial movement per revolution as the distance between each convolution of the coil.

A third rotatable ring is mounted adjacent one of the other rings for rotation with the axis of the third ring eccentric to the other rings. A link connects a pin carried by the third ring with the screw. Accordingly, as the brush is rotated about the periphery of the winding by the pair of spaced-apart rings the screw rod is held against rotation about its own axis by the connecting link being fastened to the pin on the eccentrically mounted third ring which causes the brush to move one thread on the screw for each revolution that it makes about the coil. Thus, the brush is moved along the axis of the coil and about the periphery thereof in a helical path which corresponds to the helically wound coil.

A further feature of the invention resides in preventing the induction of circulating currents in the rings and other portions of the autotransformer which encircle the leg of the core by forming some portions of non-magnetic, non-conducting material and other portions with insulating segments to avoid a closed conducting loop.

While the instant embodiment of the invention describes an autotransformer, it is within the scope of the invention to utilize a transformer having primary and secondary windings or a resistor in which no magnetic core is present.

Other features and advantages of the invention will be apparent from the specification and claims when considered in connection with the drawing in which:

Figure 1 is an elevation of a variable autotransformer, shown partly in section.

Fig. 2 is a view taken on the line 2—2 of Fig. 1.

Fig. 3 is a sectional view taken on the line 3—3 of Fig. 1.

Fig. 4 is an enlarged longitudinal section.

Fig. 5 is an elevation of the brushes and brush holder.

Fig. 6 is an enlarged detail taken on the line 6—6 of Fig. 5.

Fig. 7 is a fragmentary perspective view of the re-entrant ring and its associated core.

Fig. 8 is a fragmentary perspective illustration of a portion of the re-entrant ring.

Fig. 9 illustrates one form of the core of the re-entrant ring.

As shown in the drawing, Fig. 1 in particular, the autotransformer in the instant embodiment in which the brush-moving mechanism is incorporated, is generally indicated by the reference numeral 10. A hollow cylindrical tube 11 is provided which may be formed of insulating material, such as a phenolic compound, and a conducting winding 12 is helically wound on the exterior surface of the tube 11. At present, it is preferred to form the tube with a helical groove and form the wire in the shape of a helix and then snap the wire into the groove. At least the outside surface of the winding 12

60 is bare to provide a collecting surface. A rectangular magnetic core 13, preferably formed of laminated material, has one leg portion extending through the interior of the tube 11 so that the winding 12 circumscribes this leg portion. A pair of channels 14, one of each of which is positioned against each vertical side of the bottom leg of the core 13, and are clamped together with the core therebetween as by a nut and bolt 14a. The upper edges of the channels 14 have apertures through which bolts 14b pass to be threaded into a support plate or base 15 of the tube 11. In order to provide for conduction of the current from the commutating surface of the

winding 12, a brush holder 16, having brushes 17, is mounted for rotation about the periphery of the tube 11.

The mechanism for actuating the brushes is such that it will cause the brushes to be rotated about the winding and also be moved axially of the winding the distance between one turn and the next for each revolution of the brush about the winding. The brush in its movement from one end of the winding to the other is constantly in contact with only a portion of one turn of the winding since it moves in a helix having a pitch the same as the winding and thus there is prevented any short-circuiting of a turn by the brush being in contact simultaneously with two adjacent turns.

This brush actuating mechanism includes a ring gear 18, located adjacent the bottom end of the winding, and an upper ring 19, mounted adjacent the upper end of the winding with both rings being mounted for rotation about the winding. Spacer rods 20 extend between the two rings and move with them relative to the stationary tube 11. A pinion gear 22 is provided, which meshes with teeth 21 formed on the external periphery of the ring gear 18 to rotate the rings, and means are provided for operating the pinion gear. In the instant embodiment this means is illustrated simply as a handle 23, however, other driving means such as a motor may be employed if desired.

Also extending between the two rings 18 and 19 are a pair of threaded screw rods 24 and a pair of counterbalancing rods 25, these being equispaced about the rings. Each of the screw rods 24 and counterbalancing rods 25 has a lower end portion which projects through and beneath the ring gear 18 and to each end portion of which there is fastened a link 27. Each link is connected to a corresponding pin 28 and the pins 28 are fastened onto a ring 29. The ring 29 is mounted for rotation about an axis eccentric to the axis of the rings 18 and 19.

Accordingly, as the pinion 22 drives the ring gear 18, the rings 18, 19 and 29 rotate together about the stationary tube 11 and also the screw rods 24 and counterbalancing rods 25 will be rotated therewith about the tube 11. By reason of the eccentric mounting of the ring 29 and the connection to the screw rods 24 by means of the link 27 and the pin 28, the screw rod will be held stationary against rotative movement about its longitudinal axis. Also, the counterbalancing rods 25 are held stationary about their longitudinal axes. Accordingly, there will be relative rotation between the rings 18 and 19 and the rods 25 and 24 as the rings are rotated.

The brush holder 16 is carried by the screw rods 24 and has on each end portion a bushing 30 which screws into a threaded aperture 31 formed in each end portion on the brush holder 16. The bushing is externally threaded as at 32, and also is internally threaded as at 33. Intermediate the external threads a peripheral groove 35 is formed against which set screws 34 abut to hold the bushing stationary with respect to the holder. The threads of the screw rods 24 mate with the interior threads 33 of the bushing and, thus, as the brush holder moves about the periphery of the winding 12 for each revolution that it is rotated, it advances the holder one screw thread with respect to the screw rod. The screw threads have the same pitch as the helical winding 12 and are shown as a double thread. The internal threads of the bushing are preferably square and the external threads are preferably acme in order to provide for initially aligning the brush holder with respect to the winding though other combinations of threads may be employed provided they have different pitches to permit such adjustment.

Referring to the other views, Fig. 4 in particular, in which there is shown the details of construction of the instant embodiment of the invention, the inner periphery of the ring gear 18 has a flanged portion 36 which fits

within a raceway 37 carrying ball bearings 38. The raceway 37 is formed of two mating portions 39 and 40 held together as by screws 41. Lips 42 abut the flange 36 to hold the gear in the raceway and to provide a dust cover. The ring gear 18 is provided with an aperture 43 into which is fitted a ball bearing 44 held in place as by a C-ring 45 and an abutment 45a. The screw rod 24 has an unthreaded portion 47 consisting of an upper portion 47a, an intermediate portion 47b, and a lower square portion 47c, with each portion being successively reduced in cross-section. The flange formed between the portions 47a and 47b rests on an edge of the inner raceway of the ball bearing 44 while the portion 47b abuts the sides of the ball bearing. A bushing 46 also circumscribes the portion 47b. The extreme tip of the rod is threaded as at 49 for cooperation with a nut 50. The link 27 has a square aperture 51 into which the portion 47c fits and the link, at its other end portion, contains another aperture into which the pin 28 fits. The pin 28 is fastened to the eccentric ring 29 by means of a nut 53 screwing onto a threaded portion 52 of the pin 28. The effective length of the links between the rod 24 and the pin 28 is substantially equal to the amount of eccentricity between the rings 18 and 19 and the ring 29.

The eccentric ring 29 on its inner periphery has a flange 54 mounted for engagement with balls 55, the balls being part of a ball bearing. Holding the balls in place are two mating portions 56 which have depending lips 56a to prevent shifting of the ring 29 and to provide a dust cover. Screws 58 hold the mating portions 56 together. A circular end plate or base 59 is mounted adjacent the portion 56 and screws 60 pass through the end plate 59, the two mating portions 56 and the two mating portions 39 and 40, and thread into the tube 11 to thus maintain the parts securely connected to the tube 11. The tube 11 is formed with a step 61 which abuts the mating portion 37 to form a surface against which the portions may be forced by the screws to be held in place.

The upper ring 19 has an aperture 62 into which a ball bearing 63 is positioned. The upper end of the screw rod 24 fits within the ball bearing. The inner periphery of the ring 19 has a flange 65 which fits into a ball bearing raceway for engagement with ball bearings 66. The raceway is formed to have a center portion 67 and upper and lower lip portions 68 and 69. A spacer ring 70 abuts the upper portion 68 and on top of the spacer ring is mounted a clamping block 71 for holding in place an annular re-entrant ring 72. The parts are clamped to the tube 11 as by screws 73 threading into the tube 11 and a step 74 formed in the tube 11.

Referring to Fig. 1, the spacer rods 20 are connected to the ring gear 18 and the upper ring 19 by screws 75. Since these rods remain stationary with respect to the rings 18 and 19, there is no necessity for providing for a rotatable connection.

However, the counterbalancing rods 25, since they rotate with respect to the rings, pass through bushings 76 formed in the upper ring 19 and the ring gear 18.

Shown in Figs. 3, 4 and 5 are details of the brush holder 16. The carbon brushes 17 are forced against the helical winding 12 by means of a plurality of springs 77, there being one spring for each brush. Each brush consists of a carbon portion 78a fixed to a copper brush retainer 78. The brushes are positioned in slots formed in the holder 16 and a plate 79 is fastened to the holder to maintain the brushes therein. The plate 79 is preferably formed of copper. A lead 81 is connected between each brush retainer 78 and the copper plate 79 as by soldering to permit conduction of electric current. The brush holder 16 is arcuate and the brushes are inclined on a line having the same pitch as the turns of the winding 12.

The brush holder holding the brushes is preferably formed of three portions, the main portion 16a, a slot

forming portion 82 and the plate 79. The sides of the slot forming member 82 and the adjacent sides of the main portion 16a of the holder have a tongue and groove connection 84. As shown in Fig. 3, the spacer rods 20 pass through the holder 16 at the junction of the tongue and groove connection 84. Each tongue has fixed thereto a carbon brush 82a which rides on the corresponding spacer rod 20. The brushes 82a are so positioned that the reaction force of the springs 77 causes the brushes 82a to bear against the spacer rods. When it is desired to change the brushes 17 only the plate 79 has to be removed. To change the brushes 82a only the two spacer rods have to be removed in order to provide for the insertion of a new slot forming member 82. Accordingly, the need to readjust the position of the brush holder with respect to the screw rods 24 whenever brushes are changed is obviated by the above construction.

As shown in Fig. 1, a lead 85 extends into the interior of the tube 11 to connect with the lower end of the winding 12 and another lead 86 is connected to the upper end of the winding. Another lead 87 is connected as by soldering to the stationary re-entrant ring 72. The leads, if desired, may be connected to a terminal box (not shown). There is also shown a plurality of leads which serve as taps to the winding 12.

In order to transmit the current from the brushes 17 to the re-entrant ring 72 the upper ring 19 has a conducting plate 90 which engages the end portions of the two spacer rods. A lead 92 connects the plate 90 to a brush retainer 94 carrying a brush 95. A spring 96 biases the brush retainer 94 carrying the brush 95 upward into engagement with the re-entrant ring 72. The plate 90 is formed with lips 97 which limit the outward movement of the retainer 94 and brush. Accordingly, current can be conducted from the brushes 17 to the brush retainers 78 and then by the copper lead 81 to the plate 79. Thence, it is conducted by the slot forming portion 82 to the brushes 82a and hence to the two spacer rods 20. The spacer rods conduct the current to the plate 90 and the current can then pass to the brush 95, the re-entrant ring 72, and to the output lead 87.

The re-entrant ring in the present embodiment is similar to that disclosed in application, Serial No. 467,781, above-mentioned and now abandoned, in that it is formed with a plurality of broken annular rings. The exterior surface of the ring is composed of a plurality of U-shaped members 98 having angled ends with flat connecting links 99 extending from the end of one leg of one member to the opposite end of the leg of the adjacent member. The links 99 constitute a conducting surface on which the brush 95 rides. More specifically, shown in Figs. 7 and 8 are two views of the re-entrant ring which were taken from the above-noted application, with the connecting links 99, however, being disposed in a radial plane. It will be appreciated that the members 98 and 99 form a continuous toroidal winding. The re-entrant ring has a paramagnetic core 100 formed of flat annular stampings 101 of paramagnetic material with each interrupted by a chordally disposed slot 102, with the slots on adjacent stampings being preferably in circumferentially spaced relation. These stampings are axially spaced by intervening insulating strips 103 and an insulating cover 104 insulates the toroidal winding from the core. Thus the re-entrant ring is composed of an annular paramagnetic core formed of ferromagnetic material having a continuous toroidal winding wound thereabout.

The rings 18, 19 and 29, the tube 11, and the base 15 encircle the leg of the core 13 and thus would be subject to the magnetic influence of the core which would cause induced currents to be set up in the parts. However, according to the present invention, the parts are formed of a non-magnetic, non-conducting material such as a phenolic compound. The balls of bearings 38, 55 and 66 are of steel but are maintained in a discontinuous

ring by a plastic ball retainer ring. There is thus current induced only in the winding and in the re-entrant ring.

There has been disclosed a variable autotransformer in which there is provided a simple, efficient and extremely compact mechanism for causing a brush to move in a helical path so as to be in contact with only one turn of the winding at a time. The mechanism is such that it will function reliably and troublefree over a long period. In addition, any annular portion except for the winding and the re-entrant ring which encircle the magnetic core is formed to prevent the inducing of circular currents, though obviously when the brush actuating mechanism is utilized without a magnetic core as in a resistor, the need for prevention of the induced circular currents is obviated.

Variations and modifications may be made within the scope of the claims and portions of the improvements may be used without others.

I claim:

20 1. In combination with a variable transformer having a helical winding and a brush operable on the winding, a brush actuating mechanism for moving the brush in a helical path to engage only one turn of the winding at a time comprising a pair of spaced-apart ring members mounted for rotation, a screw rod extending between the members and having a pitch substantially equal to the pitch of the winding, a brush carrier formed with a threaded aperture through which the screw rod is threaded, a third ring mounted for rotation on an axis 25 eccentric to the axis of the other rings, a pin carried by the third ring and a link connected between the pin and the screw rod for maintaining the screw rod stationary on its longitudinal axis as it is rotated about the winding, and means for rotating the rings, whereby the 30 brush carrier is caused to move in a helical path in contact with only one turn of the winding at a time throughout its limits of movement.

2. The invention as defined in claim 1 in which the transformer has a magnetic core and the rings encircle 40 a portion of the core, said rings being formed to have at least a portion thereof of non-conducting material whereby induced currents are prevented.

3. A mechanism for causing a brush to traverse a helically wound coil in contact at all times with only one turn of the coil comprising a pair of spaced-apart rings, 45 means on one of the rings to provide rotation of the rings, at least one screw rod connected to the two rings and extending therebetween, a brush holder positioned between the two rings and having a threaded aperture through which the screw is threaded, a third ring mounted 50 for rotation on an axis eccentric to the axis of the other rings, a pin carried by the third ring, and a link connected between the pin and the screw rod, said link being effectively equal in length to the amount of eccentricity thereby preventing rotation of the screw rod about its own axis as it is rotated about the axis of the rings whereby the brush is caused to move in a helical path upon rotation of the rings.

4. A variable autotransformer comprising a closed 60 magnetic core, a tube formed of insulating material encircling at least a portion of the core, a helical winding positioned on the exterior of the tube, a ring mounted on the tube for rotation adjacent each end of the tube, a spacer rod extending between the rings, a screw rod having a pitch substantially equal to the pitch of the 65 winding extending between the rings, a brush carrier formed with an aperture through which the spacer rod extends and a threaded aperture through which the screw rod is threaded, a brush carried by the brush carrier for engagement with the winding, spring means 70 for biasing the brush into engagement with the winding and for biasing the brush carrier into sliding electrical engagement with the spacer rod, a third ring mounted for rotation on the tube on an axis eccentric to the axis 75 of the other rings, a pin carried by the third ring and a

link connected between the pin and the screw rod, means for rotating the three rings to cause the brush to be moved in a helical path to be in contact with only one turn of the winding at a time throughout its length of movement, said three rings being formed of non-conducting material, a stationary re-entrant ring mounted adjacent the end of the tube, a brush carried by one of the first two mentioned rings and in electrical engagement with the re-entrant ring, and means electrically connecting the first named brush to the brush carrier and the spacer rod to the last named brush whereby electrical current may be conducted from the winding to the re-entrant ring.

5. An adjustable autotransformer for producing a substantially stepless variable voltage comprising a helical winding, a paramagnetic core extending through the winding, a brush engageable only with part of a turn of the winding, means for moving the brush throughout a substantial length of the winding in slidable contact therewith, a closed winding comprising an annular paramagnetic core and a closed toroidal winding wound thereabout with the closed winding encircling a portion of the core and in spaced relation to the helical winding, a second brush in slidable contact with said closed winding, means electrically connecting the two brushes, input leads to the end portions of the helical winding, and an output circuit including a lead to the closed winding and one of the input leads.

6. In combination with a variable transformer having a helical winding and a brush operable on the winding, 30

5
10
15
20

a brush actuating mechanism for moving the brush in a helical path to engage only one turn of the winding at a time comprising a member mounted for rotation about the axis of the winding, a screw rod carried by the member and extending along the longitudinal axis of the winding and having a pitch substantially equal to the pitch of the winding, a brush carrier formed with a threaded aperture through which the screw rod is threaded, means for rotating the member, means to maintain the screw rod stationary on its longitudinal axis as it rotated about the winding whereby the brush carrier is caused to move in a helical path in contact with only one turn of the winding at a time, and in which there is a bushing positioned in the threaded aperture formed in the brush carrier, said bushing having internal threads matching the threads on the screw rod and external threads mating with threads formed on the brush carrier, said external and internal threads having different pitches to effectuate alignment of the brush carrier between the screw rod and the winding.
